[57] CLAIM

The ornamental design for a holder for fishing lure and leader, as shown and described.

DESCRIPTION

FIG. 1 is a perspective view of a holder for fishing lure and leader embodying my new design; the broken lines illustrating use of the invention with a hook, lure and leader thereon are for illustrative purposes only; FIG. 2 is a top plan view of the article in FIG. 1.

FIG. 3 is a side elevational view of the invention with a cover member in place and partially cut away.

FIG. 4 is a bottom plan view of the device for the invention.

FIG. 5 is a top plan view of the device for the invention.
